UNITED STATES PATENT OFFICE.

WILLIAM KEAYS BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A DWELLING-HOUSE.

SPECIFICATION forming part of Design No. 19,454, dated December 3, 1889.

Application filed November 7, 1889. Serial No. 329,589. Term of patent 3½ years.

To all whom it may concern:

Be it known that I, WILLIAM KEAYS BENEDICT, of the city, county, and State of New York, have invented and produced a new and original Design for the Exterior of a Dwelling-House, of which the following is a specification, reference being had to the accompanying drawings, forming a part thereof.

Figure 1 represents a front elevation of a house of my design. Fig. 2 is a right-hand side view of the same. Fig. 3 represents a horizontal section or plan of the first story, and Fig. 4 represents a horizontal section or plan of the second story.

Similar letters of reference designate corresponding parts in all the figures.

A house of this design is of L form in plan. It consists of two stories with an attic third story within a hipped roof. The front of the first and second stories in the main body of the building is flat and the main roof hipped at each end, the first story having a portico which extends about one-third the width of the front, the second story having a balcony over said portico, and the attic story having a dormer in the center of the front and two dormers in each end of the roof, the rear extension, which forms the L with the body, being somewhat lower than the main body and having its roof hipped at the rear, and there being a portico of the height of the first story in the angles formed between the rear of the main body and the adjacent side of the extension, and a balcony on the second story over said portico, all as hereinafter more particularly described in detail with reference to the drawings.

A designates the body of the house, in the form of a parallelogram. B designates the L-extension. The walls of the body are flat on all sides up to the attic story, which is included in the hipped roof C. In the front of the first story, at the center thereof, is the portico D, which includes the main entrance to the house, and over this portico is the balcony E of the second story.

F designates the dormer in the center of the front C of the roof. In front of the hips e of the roof are projections a of gable form, the external profiles of which are flush with the hips e. The sides of the main body A are also flat up to the attic story, and in each side there are two dormers G, projecting over the hip e of the roof. The walls of the extension B are all flat up to the attic story, the roof being hipped in the rear, as shown in Fig. 2.

H is the portico in the angle formed between the rear of the main body A and the adjacent side of the extension B. I is the balcony over said portico. On the center of the roof of the main body A of the building is an observatory J, with balustrades K.

What I claim as my invention, and desire to secure by Letters Patent, is—

The design for the exterior of a dwelling-house, substantially as herein shown and described.

WILLIAM KEAYS BENEDICT.
